UNITED STATES PATENT OFFICE.

EDWARD J. CORBETT, OF DETROIT, MICHIGAN.

DESIGN FOR A SIGNAL-LAMP CASING.

Application filed July 12, 1922. Serial No. 3,047. Term of patent 3½ years.

To all whom it may concern:

Be it known that I, EDWARD J. CORBETT, a citizen of the United States, residing at Detroit, county of Wayne, and State of Michigan, have invented a new, original, and ornamental Design for a Signal-Lamp Casing, of which the following is a specification, reference being had to the accompanying drawing, forming part thereof.

The figure of the drawing is a perspective of a signal lamp casing showing my new design.

I claim:

The ornamental design for a signal lamp casing, as shown.

EDWARD J. CORBETT.
